[57] CLAIM

The ornamental design for a machine for separating
fabric with hot air, as shown and described.

DESCRIPTION

FIG. 1 is a front perspective view of a machine for
separating fabric with hot air, showing my new design;

FIG. 2 is a front elevational view thereof;

FIG. 3 is a right side elevational view thereof;

FIG. 4 is a rear elevational view thereof;

FIG. 5 is a top plan view thereof.

FIG. I

FIG. 3

FIG. 2

FIG. 5

FIG. 4
